UNITED STATES PATENT OFFICE.

SMITH KEIGHLEY, OF INGRAM, PENNSYLVANIA.

WINDOW-FRAME AND WINDOW-SASH.

SPECIFICATION forming part of Letters Patent No. 794,024, dated July 4, 1905.

Application filed April 30, 1904. Serial No. 205,767.

To all whom it may concern:

Be it known that I, SMITH KEIGHLEY, a citizen of the United States, residing at Ingram, in the county of Allegheny and State of Pennsylvania, have invented certain new and useful Improvements in Window-Frames and Window-Sashes; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to certain new and useful improvements in window-frames and window-sashes; and the main object of my invention is to provide a window frame and sash which will be fireproof, the construction of the frame and window being such that the same is applicable to buildings of the ordinary construction; and a further object of my invention resides in the simplicity of construction and durability.

Another particular feature of my invention resides in the provision of novel means whereby the frame of the window may be adjusted in such a manner as to correspond to and align with the general construction lines of the building—that is, heretofore in the construction of building a prescribed amount of time has been allowed for the building to "settle," and by using my improved window-frames the same can be immediately constructed in the building and afterward adjusted to the building when the same has settled, and the compensating attachment of my improved window-frame permits the same to be adjusted at all times whenever it is found that the sashes of the frame are out of alinement with the frames or in any other manner refuse to work therein.

Particular attention is also directed to the fact that I employ weather-strips in connection with my invention, these weather-strips being located upon the sides of the sashes and also upon the meeting-rails, and with the above and other objects in view reference will be had to the accompanying drawings, forming part of this application, wherein like numer-

als of reference indicate like parts throughout the several views, in which—

Figure 1 is a fragmentary sectional perspective view of my improved sash and window-frame. Fig. 2 is a vertical sectional view of my improved frame and sashes, intermediate parts being broken away; and Fig. 3 is a transverse sectional view of the frame and one of the sashes.

To put my invention into practice, I construct the window-frame and window-sashes of a light sheet of metal, the metal being bent to conform to the different shapes, angles, and objects desired, and in carrying out my invention the reference-numerals 1 and 2 indicate two vertical recesses which are formed by a sheet of metal 3 and a partition 8, these recesses forming two compartments which constitute the side frames. This sheet of metal 3 is bent as shown in Fig. 1 of the drawings, the one end of the sheet of metal being formed to furnish a molding 4 upon the exterior of the building, this end or edge of the metal being bent upon itself, as indicated at 5, to receive an angled strip 6, which is U-shaped in form, the other part of the U-shaped strip being received by U-shaped member 7, similar in construction to that designated by the reference-numeral 5. The window-frame, as heretofore stated, comprises two compartments, these compartments being partitioned off by a partition 8, the one edge of which is received in a U-shaped recess 9, while the other edge of said partition is bent at an angle, as indicated at 10. This strip is loosely mounted, whereby it may move in and out to permit the adjustment of the member 6. A slot or recess 12 is formed between the side wall 14 of the sheet of metal 3 and the side wall 15 of the U-shaped member 6, and in this U-shaped recess or slot is adapted to move and operate the flange 16, carried and formed integral with the sides of the sash. The side walls of the sash are supported on their top ends by a metallic cap 17, which is also formed of one piece of material, as clearly illustrated in Fig. 2 of the drawings. The bottom ends of the sides of the frame are supported upon a metallic sill 18, this sill being filled with concrete, as designated at 19, and the top cap 100

17 and the metallic sill 18 are supported between a stone cap on the top of the frame and the stone sill upon the bottom of the frame.

5 Reference will now be had to the sashes of the window, and, as heretofore stated, these sashes have flanges 16 formed their entire length and upon both sides, these flanges being formed of metal which is bent upon itself 10 and is also formed integral with the remainder of the sash-body. The sliding surface 20 of the sash is provided with an inwardly-extending pocket or recess 21, which provides an antifrictional surface for the sash-run, and in 15 this pocket or recess can be placed the sash chain or cord if it be desired to use the same.

The reference-numeral 22 indicates the exposed inner edge of the sash, which is formed with a U-shaped recess 23 to receive the wire-glass 24, this wire-glass being of the ordinary construction and need not be further described. The bottom rail of the sash, as designated by the reference-numeral 25, is formed with a recess 26, similar in construction to the 25 recess 23, this recess serving the same function as heretofore described for the recess 23, and the bottom rail 25 is provided with a cap 27, which is secured thereon by forming U-shaped guideways 28, in which the angled 30 edges of the cap 27 are placed. The meeting-rail of the sash differs slightly in construction from the side frames of the sash and the bottom rail, and reference will be had to Fig. 2 of the drawings, wherein this construction is 35 plainly shown. The meeting-rail, as broadly designated by the reference-numeral 29, is formed of three pieces of sheet metal, the reference-numeral 30 indicating the two side walls of the meeting-rail, the lower edges of 40 these side walls being made to conform to a molding, as designated by the reference-numeral 31. The extreme edges of these side walls are bent inwardly, as at 32, and then upon themselves, as indicated at 33, forming 45 an open slot or guideway 34 for the top edge 35 of the wire-glass. The upper edges of the walls 30 are bent to form U-shaped guideways 36, in which the edges 37 of the U-shaped cap 38 are secured.

50 As heretofore stated, a particular feature of my invention resides in the weather-strip, and, as previously described, the strips are formed on the sides of the sashes by the flanges 16, which operate and move between the side 55 walls 14 and 15 of the window-frames. This form of strip practically provides a watertight connection between the sashes and the frames of the windows, and to provide a weather-strip upon the meeting-rails of the 60 sashes I bend one of the side walls 30 of the meeting-rail 29 upon itself, as indicated at 39, this portion of the wall being bent downwardly at an angle, thus forming a depending flange 65 the entire width of the sash, and to form a connection with this weather-strip I construct

an upwardly-extending flange 40 upon the side wall 41 of the meeting-rail 42.

The meeting-rail 42, which is carried by the upper sash 43, is formed of a single piece of metal, the edges of this metal being flanged together, as indicated at 43, and a suitable molding 44 is provided upon the exterior side of the meeting-rail, also a pocket or recess 45, similar in construction to the pocket or recess 26 of the bottom rail 25 of the lower sash. 75 The side frames of this sash are alike in construction, and as they are similar to the side frames described in connection with the lower sash it is needless to further describe the same. The top rail, as designated by the reference-numeral 46, is similar in construction to the meeting-rail 29, except that the weather-strip 39 is dispensed with and a cap 47 is secured upon the side walls 48 by means of the flanged connections 49.

80 Reference will now be had to a very particular feature of my invention which was briefly set forth in the objects of the invention, and by referring to Fig. 3 of the drawings the reference-numeral 50 50 represents angled lugs or angled strips which are secured to U-shaped strips by any suitable means at the side walls 14 14 of the window-frame, and the angled sides 51 51 of these lugs or strips are provided with a plurality of apertures in 90 which are screwed the ends of the screws 52 52, these screws passing through the front walls 53 53 of the window-frames, to which they are secured by washers 53^a shrunk in the inner faces of the same, and these screws carry 100 on their outer ends slotted heads 54 54 whereby they may be rotated in any desired direction. By providing a plurality of these screws extending the entire length of the window-frames I furnish means whereby the 105 wall 11 of the U-shaped member 6 may be slightly moved and adjusted to further facilitate the movement and operation of the sashes within the window-frame. In this same figure of the drawings I have designated by the 110 reference-numerals 58 58 the weights which are adapted to travel in the compartments 1 and 2, these compartments forming the weight-wells.

115 While I have herein shown and described the preferred form of construction, it is obvious that various slight changes may be made in the details of construction, in the general contour of the moldings of the sash, without departing from the general spirit and 120 scope of the invention.

125 What I claim, and desire to secure by Letters Patent, is—

1. A hollow window-frame having one of its side walls and its end walls formed from a 125 metallic sheet, said sheet being bent intermediate its ends to form an outwardly-projecting U-shaped portion, thereby forming a guideway, a strip removably secured to said ends and forming the other side wall, and a parti- 130

tion projecting into said guideway and being movable to and from said strip.

2. A hollow window-frame comprising a metallic sheet bent to form a side and end walls, a strip of metal forming the other side wall, said last-named side wall and said end walls having inturned ends, U-shaped members receiving said ends, lugs secured to said members, and screws passing through the frame and being threaded in said lugs, substantially as and for the purpose specified.

3. A metal window-frame having a hollow side frame, the inner side wall of which, opposed to the sashes, is adjustable toward and from the sashes, and a partition in said hollow side frame, dividing it into two compartments for the reception of the sash-weights, said partition being adjustable toward and from the said adjustable inner side wall.

4. A metal window-frame having hollow side frames provided with inturned guide-

ways, inner walls opposed to the sashes and having flanges in said guideways, and means operative upon the said flanges of the said inner walls to adjust said inner walls toward and from the sashes.

5. A metal window-frame having hollow side frames, provided with inturned guideways in their walls opposed to the sashes and having flanges in said guideways, said guideways and flanges forming recesses between them, and sashes having outwardly-projecting flanges forming weather-strips disposed in said recesses and movable therein when the sashes are raised and lowered.

In testimony whereof I affix my signature in presence of two witnesses.

SMITH KEIGHLEY.
